UNITED STATES PATENT OFFICE.

LEE B. INGRAM, OF LOVICK, ALABAMA, ASSIGNOR OF ONE-HALF TO J. W. STEPHEN-
SON, OF LOVICK, ALABAMA.

FRICTION CHOCK FOR CARS.

Application filed February 25, 1922. Serial No. 539,232.

To all whom it may concern:

Be it known that I, LEE B. INGRAM, a citizen of the United States of America, residing at Lovick, in the county of Jefferson and State of Alabama, have invented certain new and useful Improvements in Friction Chocks for Cars, of which the following is a specification.

My invention relates to a device for stopping or slowing up railway cars or for spragging mine cars and the like.

My chief object is to design a movable car check or stop apparatus which operates by its frictional engagement with its track supports to arrest a moving car, or to slow it up sufficiently for it to enter a switch, dump, or other place where a slow speed is desired.

A further object is to design the apparatus to slide on a main track rail with one or more of the wheels of the car to be stopped resting thereon and thereby imposing its or their weight on the apparatus so that its frictional engagement with the track is, in a measure, proportionate to the load to be arrested.

A further object is to make the track engaging bar separate from the stop element co-ordinated therewith so that by retracting the stop element the car can be permitted to run past over the bar. This gives the effect of a sprag for controlling a car, and my invention contemplates the provision of means automatically operative to retract the stop after the apparatus has slid to a predetermined point. Heretofore slowing up a car, such as mine cars, has been accomplished by an operator throwing a sprag into the spokes of the moving car, thereby causing the car wheel to drag until a sufficient reduction of speed is attained. The operator then loosens the sprag with his foot and withdraws same allowing the car to proceed. While a great degree of dexterity is attained by these operators it is, nevertheless, very dangerous and my present invention proposes to reduce this risk by providing a simple and efficient machine to accomplish these results.

My invention in its preferred embodiment only will be better understood by reference to the accompanying drawings, in which:—

Fig. 1 is a plan view of my device with

the wheel chock in position on the car track 55 to engage the approaching car wheel.

Fig. 2 is an elevation of Fig. 1, showing in dotted outline the car wheel in engagement with the chock.

Fig. 3 is an end elevation of Fig. 1, showing said wheel outline shown in Fig. 2.

Fig. 4 is a sectional elevation of Fig. 1 taken on the line 4—4 of Fig. 3, omitting the rails.

Similar reference numerals refer to similar parts throughout the drawings.

As illustrated, I show one rail of the car track 1 laid on the regularly spaced cross ties 2 with the two supplementary rails 3 lying adjacent and parallel to said car track 70 and spiked to said cross ties. A carriage 4 with bearings 5 for axles 6 on which wheels 7 are journaled, is adapted to travel back and forth on the track formed by the supplementary rails 3, the wheels projecting 75 downwardly through openings in the carriage 4 in position to engage and travel on the tracks 3. I attach along the bottom of the carriage on each side depending angle irons 8 which receive the carriage rails 3 80 between them and hold the carriage on its track. Transversely across the center of the carriage I mount a heavy metallic guide block 9 having a channel in its underface which receives a transverse slide bar 10. 85 This bar at its end adjacent to the track 1 overhangs from the carriage and has mounted on its overhung end a chock 11. I attach to the side face of the carriage adjacent to the track rail 1 a series of channel 90 brackets 12, and each of these several brackets, which are equi-distantly spaced, carries a pin 13 projecting horizontally towards the track rail 1. These several pins are likewise equi-distantly spaced and are adapted 95 to be received in sockets in a friction slide bar 14. This bar 14 has a heavy down-turned flange which is provided with sockets to receive the pins 13 and, the sockets being equi-distantly spaced, the slide friction 100 bar can be adjusted to extend its forward end farther from the stop so as to bring more than one wheel to rest thereon if desired.

I mount on the side of the chock 11 bearing lugs 15 between which I pivotally mount a push bar 16 having its free end inturned towards the track rail 1 and disposed in

position to engage the outer side of a wheel at the time in engagement with the chock. The other end of the push bar 11 pivotally connect by a link 17 to a bell crank 18 pivotally mounted at 19 on the block 9 and having one end projecting laterally away from the track rail 1 in position to engage a fixed stop 20, or to be pulled back to dotted position by a chain 21 under manual control or which may be connected to some suitable anchorage. The angle brackets 12 support the friction bar 14 sufficiently spaced from the block 9 to permit the slide bar 10 to retract the chock into dotted position, Fig. 3, against the block when it will be clear of the main track rail and under such conditions the wheels of passing cars can roll over the friction bar 14 without injury to the latter and without derailing the car.

20 I provide a hook 22 for the reception of any suitable haulage means by which the carriage can be pulled back along its track to the initial operating position desired for it.

25 In operation, the apparatus is disposed with the friction bar 14 overlying the main track rail 1 and with the chock 11 moved into position above the track rail 1 and resting on the friction bar. As a car approaches its forward wheel riding the track rail 1 passes onto the friction bar and then engages the chock 11, whereupon the momentum of the car will drive the chock, friction bar and carriage lengthwise along the track and the weight of the car resting on the wheel on the bar 14 will be imposed on such friction bar and will thereby control its frictional engagement with the track and so determine the length of movement of the carriage required to stop, or to slow up to the desired extent, the moving car. Should it be desired to bring the car more quickly to rest, the friction bar 14 can be moved to a position in which it will receive and support two or more wheels of the car when its forward wheel has engaged the chock 11 and will thus impose a greater friction load on the apparatus. Should it be desired merely to slow up the car in accordance with spragging practice, the car can be released at any time by applying a pull on the chain 21 which, through the leverage mechanism shown, will force the free end of the lever 16 against the wheel as a fulcrum and will thus act to draw the chock back into dotted position, Fig. 1, which moves it from position in front of the wheel and permits the wheel to pass freely on over the friction bar 14, thereby releasing the car to move on past the apparatus. This release of the car may be accomplished automatically by using a trip post 20 to operate the bell crank 18, or by providing a limited length of chain 21 with a suitable anchorage.

60 Though I have described with great particularity the details of the embodiment of

the invention herein shown, it is not to be construed that I am limited thereto, as changes in arrangement and substitution of equivalents may be made by those skilled in the art without departing from the invention as defined in the appended claims. 70

Having thus described my invention, what I claim as new and desire to secure by Letters Patent, is:—

1. A friction car stop comprising a friction bar adapted to slide in engagement with a car track rail, and a laterally movable chock connected to said bar and adapted in operative position to arrest a car with a wheel thereof resting on said bar. 75

2. A friction car stop, according to claim 1, having means to shift the chock to release the car, said bar being adapted to permit the car wheels to pass on over it. 80

3. In a device of the character described, a friction bar mounted to slide on a car rail track, and designed to permit a car wheel to pass over it, in combination with a chock connected to the bar, and movable relatively thereto, to engage or release a car wheel on 90 said bar. 85

4. A friction car stop, comprising a movable frame, a guide for the frame parallel with the track for the car to be stopped, a friction bar on said frame adapted to rest in 95 frictional engagement on a car track rail and designed to permit a car wheel to pass onto it, and a chock movable with the carriage and adapted to be engaged by a car while the weight of the latter is imposed on 100 said friction bar. 100

5. A friction car stop, comprising a movable frame, tracks for said frame parallel with the tracks of the car to be stopped, a friction plate overhung from the frame and adapted to rest in sliding engagement on top of a car track rail and adapted to permit the car wheels to pass onto it, and a chock movable with the frame and disposed above an intermediate point of said friction bar, 105 as and for the purposes described. 110

6. In a device of the character described, a moveable carriage, guides therefor, a track engaging friction bar mounted on the carriage, and a chock movable into and out of 115 wheel engaging position above said friction bar. 115

7. In a device of the character described, a carriage having roller supports, a track for said carriage, a friction bar overhung from the carriage in position to engage and rest on a car track rail, and a chock mounted for transverse movement on said carriage and adapted to be shifted into wheel engaging position above an intermediate portion of said friction bar. 120

8. In a device of the character described, a carriage having roller supports, a track for said carriage, a friction bar overhung from the carriage in position to engage and 125

rest on a car track rail, a chock mounted for transverse movement on said carriage and adapted to be shifted into wheel engaging position above an intermediate portion 5 of said friction bar, and means on the carriage to retract the chock from wheel engaging position.

9. In a device of the character described, a carriage having roller supports, a track 10 for said carriage, a friction bar overhung from the carriage in position to engage and rest on a car track rail, a chock mounted on a base transversely movable on said carriage and adapted to be shifted into wheel 15 engaging position above an intermediate portion of said friction bar, and automatic means to retract the chock from wheel engaging position.

10. In a device of the character described, 20 a wheel carriage, a track support therefor, a transverse slide mounted on the carriage,

a chock mounted on an overhung end of said slide, a friction bar adjustably mounted in overhung position from the carriage and adapted to rest upon the tread of a car 25 track rail, and means to move the chock towards and from operating position above an intermediate portion of said friction bar.

11. In a friction means for braking cars, a friction bar movable in sliding engagement with the tread surface of a car track rail, a movable frame connected to said bar, a retractable chock carried by the frame and movable into position over said bar, and mechanism adapted to utilize the car wheel 30 35 as a fulcrum to retract the chock and release the wheel to pass on over the friction bar.

In testimony whereof I affix my signature.

LEE B. INGRAM.
